UNITED STATES PATENT OFFICE.

WILLIAM R. JEAVONS, OF CLEVELAND, OHIO.

DESIGN FOR AN OIL-FEEDER FOR HYDROCARBON-BURNERS.

SPECIFICATION forming part of Design No. 34,039, dated February 5, 1901.

Application filed January 11, 1901. Serial No. 42,925. Term of patent 14 years.

To all whom it may concern:

Be it known that I, WILLIAM R. JEAVONS, a citizen of the United States, residing at Cleveland, in the county of Cuyahoga and State of Ohio, have invented and produced a new and original Design for an Oil-Feeder for Hydrocarbon-Burners, of which the following is a specification, reference being had to the accompanying drawing, forming part thereof, and illustrating the design in a single figure and in side elevation.

As thus shown, the design consists in the entire embodiment, constituting an entirely new and original article of manufacture and sale, and its leading and distinguishing characteristic likewise is found chiefly in the entire structure as it presents itself to the eyes rather than in any special detail thereof separately considered. This is particularly true of the design as viewed in side elevation, in which the more conspicuous features are comprised in pipe 2, stem 3, bowl 4, and a somewhat ornamental union 5, which joins said pipe and stem and gives the whole the novel appearance shown. The bowl 4 is over said stem and is marked by a distinct rim-shaped formation 6 about its top, while pipe 2 stands at an upward inclination to stem 3, with its outer end above the level of the bowl and sustaining the appearance of a handle for the other parts, suggestive of a stem to a pipe.

What I claim is—

The design for an oil-feeder for hydrocarbon-burners, substantially as herein shown and described.

Witness my hand to the foregoing specification this 5th day of January, 1901.
